UNITED STATES PATENT OFFICE.

HARRY PFANNENSTIEHL, OF EAST ORANGE, NEW JERSEY, AND ERWIN P. BANCROFT, OF BROOKLYN, NEW YORK, ASSIGNEES TO WESTERN ELECTRIC COMPANY, INCORPORATED, OF NEW YORK, N. Y., A CORPORATION OF NEW YORK.

PRINTING-TELEGRAPH RECEIVER.

1,426,768.

Specification of Letters Patent. Patented Aug. 22, 1922.

Application filed October 10, 1917. Serial No. 195,712.

To all whom it may concern:

Be it known that we, HARRY PFANNENSTIEHL and ERWIN P. BANCROFT, citizens of the United States, residing at East Orange, in the county of Essex and State of New Jersey, and at Brooklyn, in the county of Kings and State of New York, respectively, have invented certain new and useful Improvements in Printing-Telegraph Receivers, of which the following is a full, clear, concise, and exact description.

This invention relates to printing telegraphy, and particularly to an improved type of printing telegraph receiving apparatus wherein the printing of characters and various other operations are performed by power-driven mechanism controlled by line current impulses.

One of the principal objects of this invention is to provide a telegraph receiver of the above class wherein all the necessary functions are performed in a reliable and efficient manner at a high rate of speed.

Another object is the provision of means whereby the printing of one character may be effected simultaneously with the selection of the next succeeding character.

A further object is the automatic release of the printing mechanism from its upper case printing position upon the receipt of line impulses representing a word space.

A still further object is the provision of means whereby the paper or medium on which the characters are recorded will be fed forward automatically each time the type carriage is returned for the commencement of a new line.

An additional object is to provide an organization whereby a signal, such as a lamp or bell, may be caused to function in response to line impulses when the paper platen is in the upper case position without employing special cut-out mechanism to prevent printing.

To the above ends, means are provided for distributing a series of current impulses to a plurality of selecting and operation controlling magnets, which magnets control the selection of the desired character to be printed and operation to be performed.

The invention disclosed in the accompanying drawings embodies a telegraph receiving printer comprising stationary selecting mechanism, a stationary paper platen and

printing elements adapted to be moved transversely of the printer. The printing mechanism disclosed is of standard typewriter construction, and in fact, the invention is applicable to any suitable typewriting mechanism of the type-bar class.

Various mechanical functions, such, for example, as line spacing, carriage return and line spacing, character and word spacing, shift and unshift, automatic signaling, etc., are controlled by a plurality of special code bars selectively controlled by line current impulses. The various mechanical operations of the printer are performed by a battery of rotating cams cooperating with bell crank levers or suitable operative members to effect the desired operation. The cam members are mounted on a rotatable shaft to which power may be imparted by means of a motor or any suitable driving mechanism. One of the essential features of this invention is the timing of the various operations performed by the rotating cams.

The selecting mechanism consists of a plurality of stationary selecting magnets and a corresponding number of horizontal selecting bars controlled by said magnets. The selecting bars extend entirely across the printer and are adapted to be raised and lowered but are not arranged to be moved endwise.

A plurality of notched code bars or permutation bars are provided, and the arrangement of these bars with respect to the selecting bars, is such that when any combination is set up by the selecting magnets only one of the code bars will be permitted to move forward and mesh with the selecting bars. Each of the code bars controls a pull bar which is adapted to be moved forward by the code bar, when selected, into the path of a reciprocating printing bar, which printing bar is controlled by the rotating cam shaft. When a pull bar is moved forward and engaged by the printing bar, a type face carried by a corresponding type lever is thrust against the paper platen and the selected character printed. The selecting and printing operations are so timed that while one character is being printed, the next succeeding character may be selected so that there is no time lost between the selecting and printing operations.

The above and other features of this in-

vention will be fully set forth in the following description and claims, and will be more readily understood by reference to the accompanying drawings, in which Fig. 1 is a 5 perspective view of the mechanism as assembled, with certain parts broken away to simplify the drawing and to more clearly show the cooperation between the selecting mechanism and the movable type carriage, 10 and between the various stationary and movable parts; Fig. 2 is a vertical sectional view taken just to the right of the center of the group of selecting magnets of Fig. 1 and through the center of the movable type carriage. Fig. 3 is a vertical sectional view 15 through the special selecting mechanism at the left-hand side of Fig. 1; Fig. 4 is a plan view of a portion of the selecting mechanism as shown in the front of Fig. 1; Fig. 5 20 is a front view of a portion of the over-lap arrangement taken on line 4—4 of Fig. 4; and Fig. 6 is a detail view of one of the type levers.

The mechanism herein disclosed is operated 25 preferably by various combinations of five positive and negative selecting impulses with an additional impulse following each group of selecting impulses for starting the mechanism in operation. The impulses may 30 arrive over a line from a distant station and may be distributed to the selecting and starting magnets by means of a Baudot distributor, or any other of the well known distributing systems.

35 In order to simplify the drawings, the driving mechanism and a considerable portion of the frame structure have been omitted. Also various springs which would normally be used for restoring various operating parts to normal, have been omitted in order to avoid complicating the drawings. It is to be understood, however, that suitable supporting means may be provided for the selecting and driving mechanism and that 45 suitable springs may be provided wherever necessary to assist in the operation of parts or in restoring the various parts to normal.

The accompanying drawings show a stationary paper platen, a movable type carriage, and means for selectively operating the desired type carried by the movable type carriage. The movable type carriage including the type levers, bell crank levers, code bars, universal printing bar, etc., is adapted 50 to be moved from left to right transversely of the machine against the tension of a spring, one character space for each revolution of the cam shaft, and is adapted to be released and returned to its initial position 55 by the said spring, for commencing a new line. The cam shaft which performs all the mechanical operations is constantly under tension, tending to rotate. Power for rotating the shaft may be stored up in a spring 60 by means of a motor, as fully described and 65

disclosed in a co-pending application of Harry Pfannenstiehl, Serial No. 173,546, filed June 8, 1917. The cam shaft which controls the selecting operations and performs the various mechanical and printing 70 operations is adapted to be released by a starting magnet and is also adapted to be stopped once during each revolution by suitable mechanism, preferably such as disclosed and claimed in the able mentioned application. 75

Referring to the drawings and particularly to Fig. 1, the invention is illustrated in combination with a carriage of a form so well known as to require no detailed description. The type carriage 10 carrying the type bars, connecting links, code bars, etc., is supported by a portion of the frame 11 and rotatable shaft 12.

The selecting mechanism consists of five 85 selecting magnets 15, 16, 17, 18 and 19 (only two of which are shown in Fig. 1), five horizontal selecting bars 20, 21, 22, 23 and 24 extending entirely across the printer at right angles to the code bars 36, and five latches 90 25, 26, 27, 28 and 29 extending from the armatures of the selecting magnets to the selecting bars. The selecting bars are normally held in the position shown by means of the notched member 13, and when released and permitted to drop they are held in their lowered positions by means of springs 14, until restored by the upward movement of the member 13, in which position they are again held by the member 13 100 until a new selection is set up.

Another feature of the selecting mechanism is a mechanical overlap arrangement, best shown in Figs. 4 and 5, which is controlled by the rotatable cam shaft. By 105 means of the overlap arrangement provided, after a selection has been set up, a new selection may be made without interfering with or delaying the printing of the character previously selected.

Selecting and printing.

A better understanding of the apparatus may be obtained from a description of a particular type selection and the various 115 operations incident thereto.

Assume, for example, that the sending operator at a distant station is transmitting a series of impulses for selecting the character "D," and further assume that the 120 character "D" is represented by five impulses combined in the following order: positive, negative, negative, positive, negative. Also assume that at the receiving station there is a polarized line relay which 125 responds to only positive impulses, and which controls the energizing circuits of the selecting magnets 15, 16, 17, 18 and 19. Then, since the first and fourth impulses are of positive polarity, current will be 130

supplied to the selecting magnets 15 and 18, and since the second, third and fifth impulses are of negative polarity, current will not be supplied to selecting magnets 16, 17 and 19. Consequently only magnets 15 and 18 are energized. Selecting magnets 15 and 18 when energized attract their armatures and withdraw their respective latches 25 and 28 from beneath the corresponding selecting bars 20 and 23. The selecting bars 20 and 23, however do not fall the instant the latches are withdrawn because the bars are supported by the member 13, which member is controlled by the power-driven cam shaft 30. The five selecting impulses have now been received, the selecting magnets 15 and 18 have been energized and the selecting bars 20 and 23 have been conditioned for action awaiting receipt of the sixth or starting impulse. The sixth impulse effects the release of the cam shaft 30 and permits the cam shaft to start rotating. The instant after the cam shaft starts to rotate in the direction of the arrow (Fig. 2), the cam surface 32 permits vertical plunger 31 to rise under the influence of the spring connected to the pivoted arm 33. The member 13, in responding to the movement of the arm 33, is pulled down by suitable springs until the shoulder 34 carried thereby engages the frame portion 35.

The selecting bars have now been arranged to permit one and only one of the code bars 36 to move forward when released, astride the selecting bars. The code bars 36 are normally held in the position shown by the universal bar 37 which extends entirely across the type carriage in front of the extensions 38, carried by the code bars 36, the forward pull of the springs 39 being insufficient to counteract and overcome the pull of springs 40 (only one of which is clearly shown in Fig. 1).

The universal bar 37 and the printer bar 41 are moved out of their normal positions by means of a striker bar 42 which is forced downwardly by the action of cams 43-43 on the cam shaft 30. The striker bar 42 is carried by two bracket arms 44 and 45 which are pivotally secured to a supporting rod 46. The rod 46 may be journaled in the sides of the printer frame or it may be supported in any suitable manner. The bar 42 may be normally held in the position shown by suitable springs. On each of the bracket arms 44 and 45 is secured an adjustable member 47, one of which is clearly shown in Fig. 2. On the supporting rod 46 and adjacent each of the bracket arms 44 and 45 is pivotally mounted an arm 48, which arms are adapted to be engaged and operated by the cams 43-43. Each of the arms 48 carries a member 49 which is normally held in engagement with its corresponding adjustable member 47 by a spring 51, but may

be held away from the members 47 for certain purposes as will presently appear.

It will be seen by reference particularly to Figs. 1 and 2 that when the cam surfaces 43-43 force the arms 48-48 forward, the striker bar 42 will be forced downward and by acting on extensions 52 and 53 of bell crank levers 54 and arms 55, the universal bar 37 will be moved forward and the printing bar 41 will be moved upward. All of the code bars are normally held clear of the selecting bars by the universal bar 37 and when the universal bar is moved forward all of the code bars, due to the action of springs 39, will also be moved forward slightly, but only the selected code bar will be permitted to move forward astride the selecting bars. As the selected code bar moves forward extension 56 thereof engages a pin 57 on the corresponding pull bar 58 and moves its respective pull bar into the path of the reciprocating printing bar 41, so that on its downward stroke the printing bar strikes the end of the selected pull bar 58 and by means of a lever 59 connecting each of the pull bars with its corresponding type bar 60, the desired type is thrust against the paper platen in a well-known manner.

By reference to Fig. 2, it will be readily understood that in view of the pitch of cams 43-43 and the high rate of speed of the cam shaft, which speed may be assumed to be at least 600 R. P. M., the downward movement of the striker bar 42 is very rapid and consequently the forward and upward movements of the bars 37 and 41 respectively are equally rapid. By the proper selection of springs 40 and 61 these bars may be returned to normal with equal rapidity, and in fact, it is desirable that the springs 61 be of such strength that the printing bar will strike the selected pull bar with such force that the pull bar will be thrust ahead and caused to disengage itself from the printing bar and permit the springs 62 to return the actuated pull bar to normal position as the selected code bar is restored by the universal bar 37 under the action of springs 40. The quick action of the printing bar causes the selected type bar to be thrown against the paper platen with sufficient force for mainfolding and may also be sufficient to cause the type bar to return to normal due to rebound, or the return action of the type bars may be increased by providing suitable springs such as 63, connected to each of the connecting links 59.

The function of the code bars is to move the pull bar corresponding to the character selected, into the path of the reciprocating printing bar 41. Therefore, as soon as the particular pull bar has been engaged by the printing bar, the selected code bar

should be withdrawn so that the selecting bars may be restored and a new selection set up. The springs 40 should therefore be of such strength as to restore the universal bar 37 the instant the printing bar engages the selected pull bar. Immediately after the selected code bar is withdrawn by the universal bar 37, the cam 32 acting upon the plunger 31, rocks the member 33 and raises the notched member 13 to restore the selecting bars to normal, ready for a new selection.

Spacing.

15 Spacing between characters is effected by the cam shaft and in the embodiment disclosed, the type carriage is moved forward one step or one character space immediately after each character is printed. A 20 pivotally mounted rod 64 is provided, which may be journaled in the frame of the printer or supported in any suitable manner. Rigidly secured to the rod 64 are two bracket arms 65 (only one of which is clearly 25 shown), which carry a rack 66. To the free end of an operating lever 67 is connected an arm 70, on the end of which is a pawl 71 adapted to engage the teeth of the ratchet 72 whenever the arm 70 is moved forward 30 by the action of cam 73 acting on the arm 67. The arm 67 is provided with a spring 74 (Fig. 3) for operating the pawl and ratchet when the arm 67 is permitted to return. The 35 rotation of the ratchet 72 effects the rotation of the shaft 12, and by means of a worm-wheel 75 mounted thereon cooperating with the rack 66, the type carriage 10 is moved to the right one step, or one character space, for each revolution of the cam shaft.

40 The spacing mechanism is so arranged that the type carriage will be stepped ahead immediately after a character is printed, although spacing between characters may be effected, if desired, before the printing 45 of each character.

Overlap arrangement.

The function of the overlap arrangement and the locking mechanism is to make possible the selection of a new character while the preceding character selected is being printed. Each of the latches 25 to 29 inclusive is provided with a spring 76 (Fig. 4) normally tending to pull the latch sidewise 50 so that when the latches are withdrawn, by means of the selecting magnets, from beneath the selecting bars, the extension 77 carried by each of the latches will be drawn over back of the frame portion 78 and will 55 remain locked in their withdrawn positions until forced sidewise again so that the extensions 77 will clear the frame portion 78. As soon as the latches are unlocked or the extensions 77 are moved away from engagement with the frame 78 they will be re-

turned, by the action of the springs 79 connected to the armatures of the selecting magnets, until the bent-over portions 80 (Fig. 5) abut against the selected bars, in which position the latches will be held until the 70 selected bars are restored to normal, thereby permitting the latches to move in under the restored bars, providing a succeeding selection does not interfere with the complete return of the latches. When the member 13 75 is released by the rockable arm 33 it is pulled downward by the action of spring 81 until the off-set portion 34 engages the frame portion 35 (as clearly shown in Figs. 1 and 5). As the member 13 moves downward, the 80 pawl 82 carried thereby engages the end of a sliding member 83 carrying a plurality of extensions or an extension corresponding to each of the latches 25 to 29 inclusive. As above stated, when the latches 25 to 29 inclusive are actuated they are also drawn to the left by the action of springs 76, and remain locked against the frame portion 78 until they are moved to the right or released. The 85 slideable member 83, in its downward movement, due to the corresponding movement of member 13, causes the extensions carried thereby to engage the beveled end portions of the latches 25 to 29 inclusive, thereby forcing them sidewise until the extensions 77 clear the frame portion 78, thereby permitting the latches to return to normal. The members 13 and 83 and pawl 82 are so arranged that the member 83 is forced downward just far enough to free the selected latches 25 to 29 inclusive when the extension 84 of pawl 82 engages the frame portion 85, thereby releasing the slideable member 83 and permitting it to return to 90 normal under the action of spring 86. 105

If a succeeding selection coming before the selected bars are restored, utilizes one or more positive impulses corresponding to one or more of those of the preceding selection, then the latches will be actuated by 110 their respective magnets and will remain in their actuated positions until the member 83 is again forced downward due to the action of the rockable member 33 and sliding member 115 13. The operation of the member 83 should take place preferably immediately after the selected bars are actuated so that the released latches may return and abut against the selected bars and be in position to respond to the next selection if required, 120 or to move under the bars the instant they are restored to normal if they are not required for the succeeding selection. By means of this arrangement, a new selection may be set up while the preceding character 125 selected is being printed. Thus, it will be seen that the purpose of the locking and restoring means for the latches is two-fold. First, by locking the latches in their actuated position until the selected bars are low- 130

ered by the action of the cam shaft, they prevent the latches from returning and interfering with the downward movement of the selected bars; and secondly, by releasing 5 the latches as soon as the selected bars are lowered, they place the latches in readiness to move in under the selected bars the instant the latter are restored, or one or more of the latches may again be selected and 10 locked up without first moving under the selecting bars, providing the succeeding group of selecting impulses has one or more positive impulses in common with those of the preceding group. This feature, when 15 combined with a type bar printer which has an inherent overlap, permits an exceptionally high rate of speed to be attained.

Auxiliary selections.

20 In addition to selecting and printing various characters and providing means for spacing between characters and words as hereinbefore described, there are various mechanical operations to be performed, 25 such for example, as, line spacing or paper feed, carriage return and line spacing, shift and unshift (that is, shifting from lower case to upper and vice versa), automatic signaling, etc.

30 To the left-hand side of Fig. 1 is shown a plurality of special code bars 87, 88, 89, 90, 91 and 92, which are similar to the code bars 36 mounted on the movable type carriage 10. The special code bars are adapted to slide in 35 recesses provided in stationary supports 93 and are selectively controlled by line current impulses in the same manner as the character code bars 36. That is, the various mechanical functions are selectively controlled 40 by code signals which are transmitted in the same manner and by the same means as the various character signals. Also the power for performing the various mechanical functions is supplied by the rotary cam shaft, 45 as described in connection with character printing.

Type carriage return and line feed.

When it is desired to return the type carriage to the left to commence a new line, it is also necessary that the paper platen be rotated in order to feed the paper forward to present a clean surface for the next line of characters. This is usually accomplished by 50 sending one group of impulses over the line to effect the return of the type carriage and another group of impulses to cause the rotation of the platen. By means hereinafter described, both operations may be effected 55 simultaneously and by one group of signaling impulses.

The return of the type carriage and the feeding of the paper may be accomplished by sending over the line, a group of impulses 60 to cause the selection of the special code bar

92, which group of selecting impulses is followed by a sixth or starting impulse as usual, for releasing the cam shaft. Now when the cam shaft starts rotating, a cam 107 acting upon bell crank lever 108 will 70 force the auxiliary striker bar 109 (which bar corresponds to the main striker bar 42) down against the action of suitable springs (not shown). The bar 109 acting upon bell crank levers 110 and 111 moves the auxiliary 75 universal bar 112 (which bar corresponds to the main universal bar 37) forward and permits the selected special code bar 92 to move forward astride the selecting bars 20 to 24 inclusive. As the bar 92 moves forward 80 under the action of suitable springs, it performs two functions. First, it moves a pull bar 113 forward into the path of a reciprocating member 114 carried by a bell crank lever 115 which is operated by a cam 122 on 85 the cam shaft 30; and secondly, by means of the pin or extension 116 carried thereby, it acts on the pivotally supported member 98 and moves a pull bar 95 into the path of the reciprocating member 99 carried by a bell 90 crank lever 100 which is operated by a cam 96 on the shaft 30.

The pull bar 113 is connected to the rack 66 and when the rack is pulled down by the action of the pull bar, the rack is disconnected from the worm-wheel 75 and is temporarily locked down by the locking disc member 117 carried by the shaft 12. The member 117 is normally held against the end of the rack 66 by a spring 118, as shown in 100 Fig. 1, and when the rack is depressed, the member 117 under the action of the spring 118 engages the off-set portion 119 and holds the rack in its depressed position until the type carriage is completely returned by the 105 action of a suitable spring and tape 120, whereupon the member 121 carried by the type carriage engages the disc 117, forcing it back against the action of spring 118, thereby permitting the rack 66 to return to 110 normal and engage the worm-wheel 75.

When the pull bar 95 is pulled down, it operates a pawl 101 and ratchet 97 through the connecting bell crank lever 102, connecting link 103 and arm 104, thereby effecting 115 the rotation of the paper platen 94.

It is preferable that when the type carriage is being returned ready for commencing a new line, there shall be no unnecessary friction between the stationary and movable 120 parts. Therefore it is desirable that means be provided to prevent the operation of the striker bar 42 while the type carriage is being returned. This is accomplished by providing two arms 123 (Fig. 2) rigidly secured to the rod 64 so that when the rack 66 is depressed and the rod 64 rotated, the arms 123 will act upon the members 49 and hold them out of engagement with the members 47, thereby preventing actuation of the 125 130

striker bar 42 until the type carriage is returned and the rack 66 has been released.

Line feed.

5 In order that the paper platen may be rotated to line feed at times other than when the type carriage is being returned, a special code bar 91 is provided, which cooperates with the pull bar 95 and cam 96 for 10 operating the ratchet 97. When the bar 91 is selected and permitted to move forward, it acts upon the pivotally supported member 98 and moves the pull bar 95 into the path of the reciprocating member 99 carried by 15 the bell crank lever 100, which is operated by the cam 96. When the pull bar 95 is pulled downwardly it operates a pawl 101 and ratchet 97 through the connecting bell crank lever 102, connecting link 103 and arm 20 104, thereby effecting the rotation of the platen 94. The cam surface 105 may be adjusted manually by the handle 106 for determining the extent of rotation of the paper platen for each actuation of the ratchet 97, 25 which will be clearly seen in Figs. 1 and 3.

Platen shift.

The type bars are provided with two rows of type faces, one above the other. 30 The lower row of type faces is the row generally employed. When it is desired to print from the upper row of type faces a particular group of signals is transmitted for selecting the code bar 88 which cooperates with 35 suitable mechanism to raise the paper platen so that when the type bars are operated, the type faces of the upper row will be pressed against the platen. When the code bar 88 is selected and permitted to move forward, 40 it engages the arm 124 which rocks the supporting rod 125 carrying the arm 126 and moves the pull bar 127 into the path of a reciprocating striker bar 128, which is carried by a bell crank lever 139 operated by a 45 cam on the shaft 30. When the pull bar 127 is operated by the striker bar 128, it rocks the arm 129 which is pivotally supported by the frame of the printer at 130 and elevates the frame 131 which supports the paper 50 platen 94. From Fig. 1, it will be seen that the supporting frame of the platen is supported by parallelogram bars 132 and 133 connected to the frame of the machine in such a manner that when the platen is shifted it will be raised vertically and the alignment of the type will not be destroyed. When the arm 124 is moved forward, it is held by a suitable pawl 134 and consequently the arm 126 and pull bar 127 are locked 55 in their forward positions until the pawl 134 is released. Furthermore, when the arm 126 and pull bar 127 move forward, a locking member 135 under the influence of a spring 136 is permitted to rotate until the 60 pawl 137 strikes against an extension 138

of the bell crank lever carrying the reciprocating bar 128, where it is held until the bell crank lever is actuated by a cam on the shaft 30, when the extension 138 is moved back sufficiently to permit the pawl 137 to 70 engage the extension 138 and thereby hold the pull bar 127 in its actuated position. The holding pawl 137 does not lock the extension 138 back until the striker bar 128 has moved the pull bar 127 to its extreme downward position and consequently has effected a complete shift of the paper platen. Thus it will be seen that the platen will be held in its shifted position for printing a number of characters from the upper row of 80 type faces until the pull bar 127 is released, which takes place when an unshift signal or a spacing signal is transmitted.

Platen unshift.

To unshift or return the platen to normal, it is only necessary to unlock the mechanism which holds the platen in the shifted position. Two separate means are provided for operating the unshift mechanism, depending upon whether it is desired to unshift without spacing or to unshift and space at the same time. To unshift without spacing, a group of impulses may be transmitted for selecting the code bar 90, which, 95 when permitted to move forward, raises the holding pawl 134 from engagement with the arm 124, as clearly shown in Fig. 3, and permits the arm 126 (Fig. 2) to return to normal, thereby rotating the member 135 100 and disengaging the pawl 137 and extension 138. The instant the extension 138 is released, the platen 94, pull bar 127, bell crank lever 139, etc., all return to their normal positions. If it is desired to unshift 105 and space, as when punctuating or placing a comma, semicolon, period, etc., after a word (which special characters are always carried in the upper case position) and then provide the usual space between words, 110 this may be accomplished by selecting the code bar 89 which, when permitted to move forward, likewise raises the holding pawl 134 from engagement with the arm 124 and permits the arm 126 to return to normal, 115 thereby rotating the member 135, causing the disengagement of pawl 137 and extension 138 and the return of the paper platen 45, pull bar 127, bell crank lever 139, etc., to 120 normal. The code bar 89 is the only one 120 of the special code bars not provided with an upwardly extending arm to prevent the operation of the spacing mechanism.

Automatic signaling.

125 It is important that the sending operator be able at all times to signal the receiving operator. For this purpose a bell 140 and tapper 141 is provided under the control of the special code bar 87. If the sending 130

operator desires to signal the receiving operator while the printer is operating in the lower case position, it is necessary to first send a group of impulses to operate 5 the shift mechanism and then a separate group of impulses to operate the signal. As clearly shown in Fig. 1, the signal can only be operated when the printer is in the upper case position. When the shift mechanism 10 is operated, the special code bar 88 in moving forward engages the arm 124 (as hereinbefore explained) and in its forward movement raises the extension 142 from engagement with the arm 143 so that when the 15 signaling impulses are transmitted to select the code bar 87, it will move forward and by engaging a pin 144 carried by the arm 143 will cause the operation of the bell 140. The special code bar 87 is cut away or notched 20 the same as one of the regular character code bars 36, which bar corresponds to the type bar carrying the character J. Therefore, when it is desired to select the character J, which character is carried in the lower 25 case, it is obvious that some means must be provided to prevent the forward movement of the special code bar 87. The extension 142 is provided for this purpose, that is, to prevent the forward movement of the special 30 code bar 87 when the printer is operated in the lower case and the character "J" is selected. When the printer is operating in the upper case, the shifting mechanism having been operated, has raised the arm 143 35 out of the path of travel of the member 143 so that if the bell signals are transmitted while the printer is in the upper case position, the special code bar 87 will be permitted to move forward and directly effect the 40 operation of the bell 140. In order to prevent the upper face of the type bar carrying the character "J", from striking against the paper platen when a bell signal is sent, the upper portion of the "J" type lever is cut 45 away, as clearly shown in Fig. 6, so that even though the "J" type lever is actuated it will not be permitted to strike against the paper platen when bell signals are transmitted.

50 When the special code bars are selected to perform the various mechanical functions herein mentioned, it is necessary that means be provided to prevent the actuation of the type carriage so that spacing does not take 55 place except when desired. This is taken care of by providing the lever 145, which operates with an arm 146 and prevents the actuating pawl 71 from engaging the teeth of the ratchet wheel 72 when any of the code 60 bars 87, 88, 90, 91 or 92 is selected. The lever 145 is pivotally mounted on the supporting rod 147 and is adapted to be actuated when any one of the five special code 65 bars moves forward so that the bent over portion 148 is moved under the arm 146,

thereby preventing the arm 146 from rotating when the arm 70 is moved forward. When the arm 146 is held against rotation and the arm 70 moves the pawl 71, the pawl 71 rides upon the cam surface 149 and prevents the pawl from engaging the teeth of the ratchet wheel 72 and consequently prevents the rotation of shaft 12 and the worm-gear 75.

What is claimed is:

1. In a printing telegraph receiver, a paper platen capable of rotation, a printing mechanism movable transversely with respect to said platen, and a plurality of means, each controlled by line current impulses for 80 effecting rotation of said platen.

2. In a printing telegraph receiver, a paper platen, a movable type carriage, means for moving said type carriage transversely of the platen in one direction step 85 by step, means controlled by a group of line current impulses to permit the return of of the type carriage and to effect rotation of the platen, and means independent of the last mentioned means and controlled by line 90 current impulses for effecting rotation of the platen.

3. In a printing telegraph receiver a rotatable cam shaft, selecting mechanism comprising a plurality of selecting bars, a plurality of latches normally engaging said selecting bars, means for withdrawing said latches from engagement with said selecting bars, extension means carried by said latches, means cooperating with said extension means for holding said latches in their actuated positions, and means controlled by said cam shaft for effecting the release of 100 said latches.

4. Printing telegraph apparatus comprising a rotatable paper platen, a traveling type carriage comprising a plurality of independent type bars, a rack, a worm-gear cooperating with said rack for advancing the carriage, and means controlled by line 105 current impulses for effecting rotation of the paper platen and for withdrawing the rack from engagement with the worm-gear to permit the return of said carriage.

5. Printing telegraph apparatus comprising a paper platen, a type carriage capable of movement transversely of said platen, means for shifting said platen, means for holding the said platen in its shifted position, and means controlled by a single group 120 of line current impulses for permitting the advance of said carriage and for releasing said holding means.

6. Printing telegraph apparatus comprising a paper platen, a rotatable cam shaft, 125 means controlled by said cam shaft for shifting the platen, means for holding the platen in its shifted position, a type carriage capable of movement transversely of said platen, and means controlled by current im- 130

pulses for permitting the advance of said carriage and for releasing said holding means simultaneously.

7. In a printing telegraph receiver, selecting mechanism comprising a plurality of selecting magnets, selecting bars controlled thereby, signaling means, a holding member cooperating with said signaling means to prevent operation thereof, a code bar controlled by said selecting bars for releasing said holding means, and another code bar controlled by said selecting bars for operating said signaling means.

8. In a printing telegraph receiver, a paper platen, signaling means, holding means to prevent the operation of said signaling means, means controlled by line impulses for shifting said platen and withdrawing said holding means, and means controlled by line current impulses for operating said signaling means, after the release of said holding means.

9. In a printing telegraph receiver, a rotatable cam shaft, selecting mechanism comprising a plurality of selecting bars, a latch individual to each of said bars and normally extending thereunder, means for withdrawing said latches from beneath said selecting bars, means for holding said latches in their actuated positions, and means controlled by said cam shaft for releasing said holding means.

10. In a printing telegraph receiver, a rotatable cam shaft, selecting mechanism, a group of independently movable printing elements responsive to said selecting mechanism, means for moving said group of printing elements in a transverse direction with respect to said selecting mechanism, and means controlled by said cam shaft for preparing said selecting mechanism for the selection of a new character before the printing of the preceding character selected thereby is completed.

11. In a printing telegraph receiver, a rotatable cam shaft, a plurality of selecting members, means responsive to a set of line current impulses for selectively releasing said members, means for restoring said members, means operated on the receipt of a second set of line impulses before the complete restoration of said members to lock said releasing means in their selected positions, and means controlled by the cam shaft for releasing said locking means.

12. In a printing telegraph receiver, selecting mechanism comprising a plurality of selecting magnets, a plurality of selecting bars, a plurality of latches normally ex-

tending beneath said selecting bars and arranged to be actuated by said selecting magnets, means for holding said latches in their actuated positions, a rotatable cam shaft, and means controlled by said cam shaft for causing the release of said latches.

13. In a printing telegraph receiver, a paper platen, a printing mechanism comprising a plurality of independent type bars movable transversely of said platen, actuating mechanism for effecting relative vertical motion between said platen and said printing mechanism, means for holding said mechanism in its actuated position, and means controlled by a single group of line current impulses for effecting relative transverse motion between said platen and said type bars and for releasing said holding means.

14. Printing telegraph apparatus comprising a paper platen, a group of printing elements movable transversely with respect to said platen, shift mechanism for effecting relative vertical motion between said platen and said printing elements, means for holding said shift mechanism in its actuated position, and means controlled by current impulses for simultaneously permitting relative transverse motion between said platen and said printing elements and for releasing said holding means.

15. Printing telegraph apparatus comprising a paper platen movable in a vertical plane, printing mechanism movable transversely with respect to said platen, actuating mechanism for effecting relative vertical motion between said platen and said printing mechanism, means for holding said mechanism in its actuated position, and means controlled by current impulses for simultaneously permitting relative transverse motion between said platen and said printing mechanism and for releasing said holding means.

16. Printing telegraph apparatus comprising a paper platen, a type carriage movable transversely of said platen, shift mechanism for effecting relative vertical motion between said platen and said type carriage, means for holding said shift mechanism in its actuated position, and means controlled by a single group of line current impulses for effecting word spacing and for releasing said holding means.

In witness whereof, we hereunto subscribe our names this 3rd day of October A. D., 1917.

HARRY PFANNENSTIEHL.
